UNITED STATES PATENT OFFICE.

MAURICE DE WITT HIRST, OF PHILADELPHIA, PENNSYLVANIA, ASSIGNOR TO THE SAFETY DRY CLEANING SYSTEM CO., OF PHILADELPHIA, PENNSYLVANIA, A CORPORATION OF NEW JERSEY.

DRY-CLEANING APPARATUS.

Application filed April 20, 1925. Serial No. 24,610.

This invention relates to dry cleaning apparatus, an object of the invention being to provide an apparatus of the character stated which will reduce to a minimum the loss of 5 cleansing fluid, permitting the latter to be used over and over again with efficient results.

My improved apparatus is particularly designed to use a cleaning fluid which is non-combustible and non-explosive, and which is 10 more expensive than gasoline, so that it is of vital importance to prevent loss of the fluid, and my apparatus is particularly designed with this end in view.

15 A further object is to provide an apparatus of the character stated which so thoroughly cleanses the articles and removes therefrom all fluid and vapor as to dispense altogether with the ordinary extractor commonly 20 employed in gasoline machines which is used in an attempt to remove the smell of gasoline from the clothing but, as is well known, this is very much of a failure in accomplishing this result.

25 A further object is to provide an apparatus of this character which not only thoroughly cleans the articles and eliminates odors from the articles when removed, but also results in a saving of time and labor and hence cost of 30 operation.

The primary object, therefore, of the invention is to improve, simplify and reduce the cost and danger incident to the employment of apparatus heretofore known.

35 With these and other objects in view, the invention consists in certain novel features of construction and combinations and arrangements of parts which will be more fully hereinafter described and pointed out in the 40 claim.

In the accompanying drawings—

Figure 1 is a view in elevation, more or less diagrammatic, of my complete cleaning apparatus;

45 Figure 2 is a view in elevation, partly in section, of my improved washer;

Figure 3 is a view in end elevation of Figure 2;

50 Figure 4 is an enlarged fragmentary view in top plan of one end of the washer, showing its driving and controlling means;

Figure 5 is a view in longitudinal section through the clutch shaft;

Figure 6 is a fragmentary detail view, illustrating the means for operating the clutch. 55

Referring more particularly to Figure 1, 1 represents my improved washer, 2 a clean fluid supply tank located at an elevation above the washer so as to feed by gravity thereto through a pipe 3 having a valve 4 therein. 5 represents a condenser, 6 a dirty fluid tank, 7 a clarifier, and 8 a still. 9 represents a vacuum pump, 10 a drain pot, 11 a fluid pump and 12 a fluid pump, the location and operation of which will be described. 60

A pipe 13 connects the bottom of tank 6 with the lower portion of still 8 and has a valve 14 therein. A pipe 15 connects the top of still 8 with the condenser 5 and has a three-way valve 16 therein, the chamber or 70 casing of said valve connected by a pipe 17 with the outlet of the vacuum pump 9.

The drain pot 10 communicates directly with the bottom of washer 1, and a pipe 18 connects the lower portion of drain pot 10 75 with fluid pump 11. An outlet pipe 19 from fluid pump 11 is connected to the top of tank 6 and has a valve 20 therein. A branch pipe 21 connects pipe 19 with the top of tank 2 and has a valve 21' therein. 80

The vacuum pump 9 above referred to has a pipe 22 connecting the same with the upper portion of the washer and constituting the inlet of the vacuum pump, while the pipe 17 above referred to constitutes the outlet pipe 85 from the vacuum pump.

A pipe 23 connects the bottom of washer 1 with the pump 12 and has a valve 24 therein. This pump 12 discharges through a pipe 25 into the bottom of clarifier 7, and the liquid 90 from the clarifier flows through a sight device 26 and through a pipe 27 back to the washer 1. This pipe 27 has a valve 28 therein.

All of the valves above referred to may be controlled from a valve-controlled panel 29, 95 located at any desired point relative to the apparatus, as illustrated diagrammatically in Figure 1.

Before describing the operation of the apparatus as a whole, I shall describe the construction of my improved washer 1 and the operating means therefor in order that an intelligent understanding of the working of the apparatus may be had. 100

In Figures 2 to 6, inclusive, I illustrate 105 in detail the construction of my improved

washer and its operating means, and particular reference is made to these figures in the drawings. In Figure 1 the washer is shown diagrammatically, no attempt being made to illustrate details of construction.

The washer 1 comprises a casing 30, preferably of cylindrical form, horizontally disposed and supported at one end by a stationary frame 31 and at its other end by a removable frame 32. The removable frame is secured to the casing 30 by a metal strip 33 which extends around the casing and is projected through perforated lugs 34 on frame 32, and securely clamped by nuts 35.

36 represents a drive shaft to which motion is transmitted by a drive pulley 37 fixed thereon. 38 and 39 represent idle pulleys driven by belts (not shown) having belt-shifting forks 40 and 41 above the pulleys, these forks operating through mechanism to be hereinafter described to shift either one of the belts onto the drive pulley 37, it being understood that at least one of the belts is a twisted belt and driven in a direction opposite to the direction of its companion belt so that motion is transmitted to drive the shaft 36 in one direction for the desired number of revolutions and then in the opposite direction for the desired number of revolutions. The drive shaft 36 is supported in suitable bearings 42 on brackets 43, the latter removably connected to the respective supports 31 and 32.

One end of the casing 30 is closed by a removable head 44, the latter secured by bolts 45 to an annular flange 46 on the casing. The other end of the casing may have a permanently attached head 47, and both of these heads have bearings 48 for the trunnions 49 at the respective ends of a rotary drum or receptacle 50.

This drum or receptacle 50 is preferably of cylindrical form, is of smaller diameter than the casing 30, and is perforated so as to allow the fluid to flow freely therethrough. These trunnions 49 are rendered water and gastight by suitable stuffing boxes 51, and large gear wheels 52 are secured on the ends of the respective trunnions.

These gear wheels 52 mesh with idle pinions 53 and 54, respectively, and said idle pinions are driven by pinions 55 and 56, respectively, both of said pinions 55 and 56 being fixed to the drive shaft 36 so that the drum or receptacle 50 is positively driven from both ends, as clearly indicated.

It is to be understood that the several gears and pinions at one end (the left-hand end of Figure 1) can be removed with the removal of the head 44 so as to allow the drum or receptacle 50 to be removed from casing 30 from time to time as may be desired.

The belt shifting forks 40 and 41 are carried by levers 57 and 58, respectively. These levers are pivotally mounted between their

ends as shown at 59 and have their shorter ends connected to a link 60. The link 60 is connected to a pivoted arm 61 located at right angles to the link 60, and said arm has a stud 62 movable in a cam groove 63 in a cam 64.

The cam 64 is secured to a vertical shaft section 65 in line with a shaft section 66, the latter carrying a worm wheel 67 in mesh with a worm 68 on the drive shaft 36.

The shafts 65 and 66 are connected by clutch members 69 and 70. The clutch member 69 has a coil spring 71 normally pressing the clutch members together, and said member 69 also has a cam flange 72 which is adapted to be moved by a movable bar 73 so as to cause the clutch members to separate.

This bar 73 is connected to one end of a lever 74, the latter pivotally supported between its ends as shown at 75. A manually movable rod 76 is connected with this lever 74 so that, by manually controlling the position of the bar 73, the clutch is caused to engage or disengage, the power of the machine being utilized to separate the clutch members due to the cam action of the flange 72 on the bar 73, it being understood that this separation of the clutch always takes place while both belts are on idle pulleys when the parts are in the position shown in Figure 4.

In order to lock the mechanism against the possibility of power driven movement, I provide on one end of the casing 30 a pivoted bracket 77 supporting a shaft 78 carrying a worm 79. A spring-pressed catch member 80 is mounted on the casing and is adapted to hold the bracket 77, either in the inoperative position shown in Figure 3, or in mesh with the gear wheel 52 as indicated in dotted lines in Figure 3.

This catch 80 is manually moved to release the bracket and allow the latter to be swung to its normal inoperative position. A hand-wheel 81 is provided on the shaft 78 to permit a manual turning of the gear 52, and hence the turning of the drum 50 to manually move the drum to any desired position.

I make no specific claim to the worm 79 and its cooperating parts as this form constitutes standard equipment in general use. I would call particular attention, however, to my improved closure for the inlet of the casing 30, illustrated more particularly in Figures 2 and 3 of the drawings.

The drum 50 must of course have some form of opening and door to admit the articles to the drum and permit their removal therefrom but as I may use any style of door I have not illustrated any particular construction for the purpose.

I do, however, make claim to the closure for the casing, and in order to provide a tight closure I supply a frame casting 82 secured to the casing 30 around an opening 83 in the casing. This casting presents a flat surface to a flat cover 84. This cover 84 may be of steel

or other flexible material, and the juncture of the parts may be rendered absolutely tight by the positioning of a gasket or packing 85 in the frame 82, as shown in Figure 3.

5 A pressure block 86 is provided, carrying a series of spring tongues 87, said tongues engaging the cover plate 84, and said block 86 engaged by screw plungers 88 carried by yokes 89. These yokes 89 are pivotally connected to the casting 82 as shown at 90 and are of such size that they may be swung longitudinally of the casing out of the way of the opening so as not to interfere with the removal and insertion of articles to be 15 cleaned.

10 The plungers 88 preferably have hand-wheels 91 thereon so that suitable pressure may be applied to the block 86 to cause the spring tongues 87 to engage the cover 84 20 with the desired resilient pressure to insure an absolutely tight closure under any and all conditions. When the plungers 88 are released the yokes 89 can be swung laterally and the cover can be removed, as will be 25 understood.

The operation of the washer briefly stated is as follows: The clothes or other articles are placed in the drum 50 and the casing tightly closed. The clutch members 69 and 30 70 are permitted to engage and motion is transmitted by the shaft 36 to alternately turn the drum first in one direction and then in the other.

35 The operation of the apparatus as a whole is as follows: Assuming the articles to be washed are properly located in the drum 50, valve 4 is opened to allow the desired quantity of cleansing fluid to flow into the washer. This valve is then closed and the washing 40 operation started. If the clarifier is used, valves 24 and 28 are opened so that during the washing of the clothes, the fluid is moved by a pump 12 from the washer through the clarifier and back to the washer. This may 45 be a continuous operation or an intermittent operation but in any event the final operation of movement through the clarifier will not cease until the sight device 26 shows that the liquid or fluid is clear.

50 Assuming that the clarifier is used and the operation completed, the pump 11 is started and valve 21' opened so that the liquid will drain into the pot 10, the latter catching buttons or other articles, and thence through the 55 pipe 19 and branch pipe 21 into the clean fluid tank. This pump 11 is then stopped and the valve 21' closed. The valve 16 is then turned so as to open communication between the pipe 17 and condenser 5, and the 60 vacuum pump 9 is started. This vacuum

pump will draw from the clothing all saturation, either fluid or gas, and will force the same into the condenser where the gas will be condensed. This operation of the vacuum pump not only conserves all fluid or gas but 65 entirely relieves the clothing of any odor and also leaves the clothes practically dry so that they are ready to be hung up for final drying.

Assuming that the clarifier is not used, the 70 dirty liquid is forced by the pump 11 into the top of dirty fluid tank 6, the valve 20 being opened. From the tank 6 the liquid flows through pipe 13 into still 8, valve 14 being opened, and from the still the cleansed gas 75 flows into the condenser 5 through pipe 15, valve 16 being properly positioned. From the condenser the liquid flows through a short pipe 5' into the clean fluid tank 2.

It will therefore be noted that my improved 80 apparatus is in a very true sense a closed system so that before the articles are removed from the washer the cleansing fluid is for all practical purposes entirely recovered, cleansed and ready for repeated use. 85

While I refer to my improved apparatus as a closed circuit or system it is obvious that a breather coil or analogous device is necessary somewhere in the system, and it is to be understood that in using this term "closed 90 system" I have in mind the provision of a breather coil or some such analogous device.

Various slight changes and alterations might be made in the general form of the parts described without departing from the 95 invention, and hence I do not limit myself to the precise details set forth but consider myself at liberty to make such slight changes and alterations as fairly fall within the spirit and scope of the appended claim. 100

I claim:

A dry cleaning apparatus, including a washer, a clean fluid tank above the washer, a dirty fluid tank above the clean fluid tank, a condenser, a still, an outlet pipe communicating with the washer, branch pipes connecting said pipe with the clean fluid tank and dirty fluid tank, respectively, valves in said branch pipes, a force pump in the first-mentioned pipe, a pipe connecting the clean 110 fluid tank with the washer, an outlet pipe connecting the dirty fluid tank with the still through which pipe the fluid is fed by gravity, a valve in said last-mentioned pipe, a pipe connecting the still with the condenser, 115 a valve in said last-mentioned pipe, and a pipe connecting the condenser with the clean fluid tank.

MAURICE DE WITT HIRST.
